UNITED STATES PATENT OFFICE.

JOHN W. LYON, OF PROVIDENCE, RHODE ISLAND.

SELF-CLOSING FAUCET.

SPECIFICATION forming part of Letters Patent No. 675,635, dated June 4, 1901.

Application filed February 4, 1901. Serial No. 45,861. (No model.)

To all whom it may concern:

Be it known that I, JOHN W. LYON, a resident of the city of Providence, in the county of Providence and State of Rhode Island, have 5 invented certain new and useful Improvements in Self-Closing Faucets; and I do hereby declare that the following is a full, clear, and exact description thereof, reference being had to the accompanying drawings, and 10 to the letters of reference marked thereon, which form a part of this specification.

This invention relates to the class of self-closing faucets in which the closing of the valve is effected by the pressure of the water 15 in the supply-pipe. It is fully described and illustrated in this specification and the annexed drawings.

Figure 1 represents a vertical section of the outer casing of the faucet and the valve and 20 other moving parts, with the valve closed. Fig. 2 is an enlarged vertical section of valve and moving parts in the lower part of the faucet, as shown in Fig. 1, with the valve open. Fig. 3 is a perspective view of the cylinder that carries the valve separate. Figs. 25 4 to 7 represent minor parts of the faucet, as will be hereinafter described.

The object of the invention is to provide a faucet that will be closed when allowed to by 30 the pressure of the water in the supply-pipe without any noise and that will not require any packing to keep it from leaking when in operation or when closed. The following is a description of its construction and mode of 35 operation:

A represents the globe or upper chamber of the faucet, with the delivery-spout C made fast in one side of it.

B is a lower chamber, to the top of which 40 the chamber A is attached by a projection S on its lower side, that screws into the top of the chamber B at y.

G is a cylinder (see Fig. 3) that is inclosed in the lower chamber B and which is held by 45 the arms a a and a collar r at the upper ends of the arms a, that screws onto the lower end of the projection S. (See Fig. 2.) A valve-seat d is made on the end of the projection S around the passage J, which connects the two 50 chambers A and B. A valve k is held on the

upper end of the stem n and is arranged to shut tightly on the seat d above it.

The valve-stem n, with the valve on it, is shown separately in Fig. 4, of which Fig. 5 is a top view. A piston V (seen in Fig. 6, of 55 which Fig. 7 is an end view) is fitted to slide closely in the cylinder G, and the stem of the valve is fitted to slide in the hole in the upper end of the cylinder with sufficient space around it to allow the water under pressure 60 to pass slowly into and out of the chamber h, made between the upper end of the cylinder G and the piston.

The piston V and the valve-stem n are made separate to facilitate the placing of them in the 65 cylinder G, which is done by putting the stem n, Fig. 4, down through the hole m in the cylinder G, Fig. 3, and then pushing the piston V up into the lower end of the cylinder on the small part of the stem n, Fig. 4, and screwing 70 the nut t on the lower end of the stem.

The pressure of the water in the chamber B, which is equal to that in the supply-pipe H, will press the piston and the valve k up against the seat d. To open the valve, a stem 75 N is inserted in the top of the upper chamber A, (see Fig. 1,) that extends down and rests on the valve k. This stem N is fitted to slide closely in a tube P, which is screwed into the top of the chamber and extends down inside. 80

The stem N is made small and tapering at its lower end to interfere as little as possible with the passage of the water from the valve, and a shoulder g is made on it to meet the lower end of the tube P, the shoulder having 85 a recess in its top to hold water to form a cushion to prevent its making a noise when it strikes the end of the tube in the closing of the valve. A knob E is attached to the upper end of the stem to press it down by. 90

To operate the faucet, the stem N is pressed down by the knob E and the valve k is pushed down from its seat d, which allows the water in the lower chamber B to flow in between the arms a a and through the open 95 valve and passage J to the upper chamber A and out through the spout C. When the pressure is removed from the knob E, the pressure of the water in the lower chamber B would instantly close the valve k again; but 100

this sudden closing, which causes a disagreeable noise and the effects of a water-hammer, is prevented by a water-cushion in the little chamber *h* in the upper end of the cylinder 5 *G*, which fills with water through the hole *m* (see Fig. 2) around the piston when the valve and piston are pushed down, and this water in the chamber slowly escaping by the annular space around the piston in the hole allows the valve *k* to close gently upon its seat without producing any shock or disagreeable noise.

Having thus described my improvements, I claim as my invention and desire to secure 15 by Letters Patent—

1. In a faucet, the combination of a case, a tube held in the top of said case and projecting down into it, a stem held to slide in said tube to operate a valve, a shoulder made 20 on said stem with a recess in its upper side open to the water in said case, to form a wa-

ter-cushion to receive the end of said tube when the valve closes, and a valve, substantially as described.

2. In a faucet, an upper chamber with a 25 valve-seat on its lower end, a tube extending down into said chamber, a stem to operate a valve held to slide in said tube, a shoulder on said stem recessed on its top side to fit over the lower end of said tube, in combination with a cylinder, suspended from said upper chamber, a piston in said cylinder, a valve on the upper end of said piston regulated in its action by the movement of said piston, in said cylinder, substantially as de- 30 35 scribed.

In testimony whereof I have hereunto set my hand this 1st day of February, A. D. 1901.

JOHN W. LYON.

In presence of—

HOWARD E. BARLOW,
EDGAR S. MARSH.
